Fig 1

Fig 2

Fig 3

Fig 7

Fig 8

FIG. 1 is a front elevational view of a height measuring ruler or similar article in a working position showing my new design;

FIG. 2 is a front elevational view of FIG. 1 with the measuring arm in a folded position;

FIG. 3 is a fragmentary front elevational view of FIG. 1 on an enlarged scale of the upper portion thereof;

FIG. 4 is a left side elevational view of FIG. 3;

FIG. 5 is a rear elevational view of FIG. 3;

FIG. 6 is a right side elevational view of FIG. 3;

FIG. 7 is a top plan view of FIG. 3 on an enlarged scale;

FIG. 8 is a bottom plan view of FIG. 7.

I claim:

The ornamental design for a height measuring ruler or similar article, substantially as shown and described.
